DOFFING MECHANISM.

1,280,381.

Specification of Letters Patent.

Patented Oct. 1, 1918.

Application filed November 2, 1914. Serial No. 869,965.

To all whom it may concern:

Be it known that we, THOMAS ALEXANDER BOYD, HAROLD ARTHUR BOYD, and JAMES BOYD, all subjects of King George of Great Britain and Ireland, residents of Shettleston Iron Works, Glasgow, Scotland, have invented a certain new and useful Improvement in Doffing Mechanism, of which the following is a specification.

10 According to this invention which refers to doffing mechanism in flier frames for spinning, twisting and the like, a bobbin carrier is used which is adapted to receive and carry an empty bobbin to the center of the spinning spindle and also to push the full bobbin which has been doffed from the said spinning spindle clear of the same. The bobbin carriers referred to in some cases are mounted behind the spindle so as to push the full bobbins to the front side of the frame and they are so arranged as to be capable of being moved to a position below and in front of the spindles to enable the worker to place the 20 empty bobbin in the said carrier. In one application of these carriers the bobbin is so held that it may be raised by the lifting rail on to the spindle, the carrier thereafter receding clear of the empty bobbin and 25 spindle.

30 Further according to this invention, when the full bobbins are pushed off the builder rails by the bobbin carrier the bobbins fall between a pair of blades placed on the top 35 of a bobbin box and passing from end to end of the frame. One of these blades is fixed along the back top edge of the bobbin box. The other blade is carried on a set 40 of levers adapted to move the said blade to the front side of the bobbin box, thus allowing space for the bobbins to fall between the two blades. At the proper moment the levers close the blades and sever the threads which extend from the full 45 bobbins to the empty bobbins on the spindles. The various operations of doffing such as the moving of the full bobbins off the spindles and the pushing of them into the box, also the moving of the empty bobbins 50 on to the spindles are effected by what is called the doffing shaft which is turned first in one direction and then in the opposite direction. According to this invention in 55 the case of frames in which the full bobbins are lowered off the spindles at their bottom end when the spindles are stopped for doff-

ing, the cylinders and spindles are reversed so that the fliers may unwind from the said full bobbins sufficient length of yarn to permit the said bobbins being lowered off 60 the spindles without at the same time carrying coils of yarn which would come over the heads of the bobbins, getting around the spindles. The lifting rails in this case are lowered by means of a let-off motion which 65 permits the traverse motion to remain at rest during the operation of doffing.

Accompanying this specification are two sheets of drawings illustrating same, and 70 in which—

Figure 1 is an end elevation of a spinning frame, partially broken away, in which my invention is illustratively embodied;

Fig. 2 is a side elevation and plan of a detail;

Fig. 3 is a detached elevation of the operative connection between shafts 9 and 15;

Fig. 4 is a front elevation of the latch for holding the lever 12;

Fig. 5 is an end elevation of the builder 80 motion;

Figs. 6 and 7 are respectively side elevation and plan of a modified bobbin carrier; and

Fig. 8 is a side elevation of the lever 12 85 and catch 23 in doffing position.

In carrying out our invention in one arrangement applicable to a worsted spinning frame in which the full bobbins are doffed from the lower end of the spindle, we employ, Fig. 1, a spindle rail 1, a spindle and flier 2, a step rail 3, a builder rail 4, also a cylinder 5 behind the spindles and a tape 6 to drive the said spindles, all of these being of ordinary and well-known 95 construction. On the frame behind the spindle 2 we mount rack shaft brackets 7 having bearings carrying rack slides 8 which are horizontal and at right angles to the foot step rail 3. These rack slides 8 are 100 placed at a suitable height to support and move the bobbin carriers hereafter described. On the under side of the rack slides teeth 8¹ are formed. Below the rack slides 8 we carry on bearings in the framing a rack shaft 9 parallel with the step rail 3. On this rack shaft 9 we mount a rack pinion 10 below each rack slide and geared to same so that by revolving the rack shaft the rack slides 8 move to and 105 from the spinning spindle 2. At the front end of the rack slides are bearings 8² in

which we place a bobbin carrier shaft 11 and on the end of this shaft is a hand lever 12 to turn the said bobbin carrier shaft 11 as hereafter described. On the bobbin carrier shaft 11 we mount behind each spindle a bobbin carrier 13 extending from the said shaft upward and forward toward the spindle. At the upper and front end of the bobbin carrier we form a cup 13² made to receive the upper end of the bobbin. The bobbin head rests in this cup and is surrounded by the sides. A hole is made in the bottom of the cup, Fig. 2 13² to clear the stem of the bobbin. The hole is cut out to 10 the periphery of the cup at its front side. It will thus be understood that the empty bobbin 14 can be passed into the cup and lowered until the top flange rests in the cup, the bobbin hanging loosely downward. The 15 lever 12 normally rests upon the bracket 24³ of a catch lever 24, hereinafter referred to. When empty bobbins are to be inserted in the bobbin carriers 13, the catch lever 24 is swung out of engaging position and the 20 lever 12 lowered by means of its handle 12² until it rests against the lower bracket 24⁴ on the catch lever 24, which has been returned to position. The lever 12 is then moved forward by rotating the shaft 9 (by 25 means of a crank handle, not shown) until the cups 13² are in accessible position. The catch 23 on the lever 12 now engages the bracket 24⁴ on the catch lever 24 and holds the lever 12 in this "out" position against 30 the pull of the counterweight 24¹ at the end of a chain passing over the chain wheel 24² fast on the shaft 9 of the rack pinion 10. After the empty bobbins have been placed 35 in position in their cups 13², the catch lever 24 is swung out of engagement with the catch 23, the lever 12 being thereupon drawn inward by the counterweight 24¹ and lifted by the handle 12² into engagement with the upper bracket 24³, as indicated in Figs. 1, 40 and 4, as shown perhaps more clearly in the drawings of our corresponding British Patent No. 19,909, of 1914. Behind the spindles we mount in bearings on the framing a doffing shaft 15 passing from end to end of the 45 frame. On this shaft we mount chain pulleys 16 with chains 17 to lower and raise the step rail 3 and also the builder rail 4, so that by turning the doffing shaft 15 by a lever or other mechanism in one direction 50 and then in the opposite direction the rails 3 and 4 are first lowered and then raised again to working position. As the builder rail 4 descends the full bobbin 18 resting on them also descends until it is clear of the spindle 55 2. On the doffing shaft 15, Fig. 3, above referred to, we also mount a chain pulley 19 and chain 20 which is carried to a chain pulley 21 on the rack shaft 9. By means of this as the doffing shaft 15 is being turned to 60 lower the rails 3 and 4 the rack shaft 9 is

also turned and moves the bobbin carrier 13 with the empty bobbins 14 toward the full bobbins 18 which are clear of the spindles when the builder rail 4 is lowered. The forward movement of the bobbin carriers 14 70 continues until they press the full bobbins 18 off the builder rails 4 causing them to fall into the bobbin box 22 hereinafter described. The empty bobbins 14 are then below the spindles 2. The lever 12 with the 75 bobbin carrier 13 is temporarily detained in this position by the catch 23 pivoted on the lever 12. This catch has a shoulder 23' and nose 23², and slides with the lever 12 on a bracket 24³ on a catch lever 24 80 pivoted on the frame. On the outward movement of the lever, the shoulder 23' of the catch 23 eventually passes the bracket 24³, and the catch drops by gravity until its nose 23² is halted by the pin 23³ on 85 the lever 12. The shoulder 23' on the catch 23 will now engage the bracket 24³ on the catch lever 24 and prevent the return movement of the lever 12 under the pull of its counterweight 24¹, thus holding the lever in 90 out position. After the full bobbins have fallen into the box 22 and the empty bobbins 14 have been thus brought to position beneath the spindles 2, the doffing shaft 15 is rotated in opposite direction in order to 95 raise the rails 3 and 4 again. As they rise, the empty bobbins 14 are lifted from the carrier 13 onto the spindles 2. Simultaneously with the rise of the rails 3 and 4, the latch 23 is freed, this being accomplished 100 by a bracket 3' fixed on the end of the step rail 3, which, as the rail rises, engages a co-operating projection 12' on the lever 12, by which the lever is lifted, carrying with it the catch 23. As soon as the shoulder 23' 105 clears the bracket 24³, the pull of the counterweight 24¹ rotates the pinion 10, thus automatically returning the lever 12 to its normal "in" position shown in Fig. 1. Below and in front of the step rail 3 we 110 fix the bobbin box 22 above referred to, extending along the front of the spindles. On the back top edge of the said bobbin box 22 we mount a flat blade of steel 25 extending along the frame. A co-operating blade 115 28, extending lengthwise of the frame, is carried in front of the fixed blade 25 by a set of swinging levers 26 centered on the shaft 27, below the bobbin box, so that the blade 28 swings across the bobbin box and 120 passes under the fixed blade 25. When the full bobbins are pushed off the bobbin rail 4 they fall into the bobbin box 22 as before described between the blades 25 and 28. The 125 yarn from the full bobbin in the bobbin box remains intact right up to the flier on the spindle 2. When the empty bobbin 14 is placed on the spindle 2 and spinning is resumed the moving blade 28 is closed by any suitable hand or foot operated mechanism 130

and grips the yarn at all the spindles, severing it from the full bobbins in the box 22 and the empty bobbins on the spindles.

When the bobbins 18 are full and ready 5 to doff from the spindles the frame is stopped and the cylinder is reversed so as to cause the fliers to unwind from the full bobbins 18 sufficient length of yarn to allow the said bobbins to descend without causing 10 the coils of yarn which would come over the head of the bobbin to catch around the spindle.

The builder rails in this machine are operated by the well-known Scaife traverse motion in which a sliding block operated by a heart cam and lever moves to and fro and by means of a chain gives an end motion to a traverse bar extending along the frame, the traverse bar in turn giving the vertical 20 motion required by the builder rails. In this case the builder rail is lowered beyond the usual movement given by the traverse mechanism. This is accomplished by means of an extension of the chain which connects the traverse motion with the builder rail.

We shall now describe how this extension of the chain is accomplished as applied to the Scaife motion referred to. We employ Fig. 5 a Scaife traverse motion of the usual 30 description with a slide 29 moved to and fro by a heart cam 30 and lever 31 giving a pulling motion to a traverse bar 32 extending along the frame and in turn operating in the usual manner the pokers of the builder 35 rail 4, Fig. 1. Instead of having the chain 33¹ referred to fixed to the sliding block 29 we mount on the sliding block a chain pulley 33 around which we carry the chain 33¹ which is to be let off to lower the builder 40 rail 4, Fig. 1, beyond its traversing movement for the purpose of doffing. The chain 33¹ is carried from the chain pulley 33 on the slide 29 referred to upward to the doffing shaft 15 where it is fixed to a chain pulley 45 33². When the doffing shaft 15 before described is turned to lower the rails it lets off the traverse chain 33¹ and so extends the chain beyond the slide block 29 and the traverse bar 32. When the doffing shaft 15 50 is turned in the direction required to raise the rails it takes up the traverse chain 33¹ to the original position.

In a second arrangement of bobbin carrier adapted to suit spools or bobbins having a flange only at one end, we employ Figs. 55 6 and 7, all the parts above described excepting the bobbin carrier 13. Instead we mount on the bobbin carrier shaft 11, Fig. 1 afore-described, a horizontal lever 34 projecting 60 forward and having at its end next to the spinning spindle a vertical stud 34¹. On this stud we mount a sliding bracket 35 the front face of same next to the spindle having an open gab top and bottom. These 65 gabs are made to suit the diameter of the

spool 36 top and bottom. The lower gab has a pin 35¹ which passes into the spool 36 and supports it vertically. The pin referred to does not penetrate into the hole of the bobbin through which the spinning spindle 70 passes. The gab at the upper end has two flat springs 37 projecting slightly in front of the bobbin on either side, the springs having sufficient flexibility to allow the bobbin carrier 34 to be drawn clear of the spool 36 75 after the latter is held by the spindle. When the spools 36 are full and the rails 3 lowered, the bobbin carriers 34 are moved to the center of the spindles, at the same time pushing the full bobbins off the builder rails 80 4. The builder rails 4 are then raised carrying the empty spool 36 and its sliding carrier 35 upward, the spool carrier 35 sliding on the vertical stud 34¹ before described. As soon as the spindles have sufficiently entered the empty spools 36 to hold them in position the bobbin carriers 34 are made to recede as in the foregoing first arrangement.

Having now particularly described and ascertained the nature of our said invention, 90 we hereby declare that what we claim is:

1. In spinning, twisting, and like frames, a spinning spindle and a top support therefor, a bobbin and a bottom support therefor, means for separating and approaching said supports, and a bobbin doffing mechanism comprising a carrier arranged behind the spindle and adapted to carry an empty bobbin, means for moving said carrier forward to present the empty bobbin substantially in alinement with the spinning spindle when said supports are separated, and means for moving said carrier to position beneath said bottom support during the spinning operation to receive an empty bobbin. 100

2. In spinning, twisting, and like frames, a spinning spindle and a top support therefor, a bobbin and a bottom support therefor, means for separating and approaching said supports, and a bobbin doffing mechanism comprising a reciprocating member, an arm pivotally mounted thereon behind the spindle and forming a carrier for an empty bobbin, means for advancing said reciprocating member to move said bobbin carrier into substantial alinement with the spinning spindle when said supports are separated, and means for swinging said carrier arm down beneath the bottom support to receive an empty bobbin in the retracted position of said reciprocating member. 110

3. In spinning, twisting and like frames, a spinning spindle and a fixed top support therefor suspending the spindle from its 125 upper end, a vertically-displaceable, bobbin-supporting builder rail and a bobbin doffing mechanism comprising a bobbin carrier arranged behind the spindle and means for moving the same forward beneath the 130

spindle when the builder rail is down to place an empty bobbin thereon and allowing the bobbin to be lifted from the carrier by the rise of the builder rail, substantially as 5 described.

4. In spinning, twisting and like frames, a bobbin box to receive filled bobbins in combination with doffing mechanism, comprising a pair of blades between which the full bobbins pass on doffing, one of said blades being 10 stationary and the other movable, said blades extending longitudinally of the frame and serving a plurality of spindles simultaneously, together with means for bringing said 15 movable blade into engagement with the stationary blade to sever the thread from the doffed bobbin after the latter has dropped into the receptacle.

5. In spinning, twisting and like frames, 20 a doffing mechanism comprising a bobbin carrier, a rack slide on which said carrier is pivotally mounted behind the spinning spindle, and means for rectilinearly displacing said rack slide to advance the bobbin carrier

beneath the spindle and retract the same 25 therefrom, for the purpose described.

6. In spinning, twisting and like frames, a top-supported spinning spindle, a builder rail adapted to be lifted and lowered beneath the same, a bobbin carrier supported 30 behind the spindle and means for advancing said carrier to position beneath the spindle, while the rail is lowered, and retracting it after the bobbin has been lifted therefrom by the rising rail, substantially as described. 35

In testimony whereof we have signed our names to this specification, in the presence of two subscribing witnesses.
